UNITED STATES PATENT OFFICE.

OTTO HAENTJENS, OF HAZLETON, PENNSYLVANIA.

LUBRICATION SYSTEM.

Application filed July 14, 1925. Serial No. 43,552.

To all whom it may concern:

Be it known that I, OTTO HAENTJENS, a citizen of the Republic of Germany, residing at Hazleton, in the county of Luzerne 5 and State of Pennsylvania, have invented certain new and useful Improvements in Lubrication Systems, of which the following is a specification.

My invention relates to lubrication systems, and particularly to the lubrication of double-action pumps of the general type illustrated in my prior Patent No. 1,489,122, April 1, 1924. The object of my invention is to provide a simple and efficient means 15 for effecting the automatic lubrication of all bearing parts of the pump from an oil supply in the crank case.

The accompanying drawing shows, in vertical section, a pump in which my invention is embodied in one form.

While the invention may be embodied in pumps of other construction than that shown, I have illustrated a pump which in general resembles that disclosed in my 25 prior patent above mentioned. It may be appropriately used as to create a vacuum through a suction line 15 which leads to any appropriate chamber, such as the casting of a centrifugal pump, from which air 30 is to be exhausted to effect its priming. The branches 16 and 17 of the suction line 15 lead respectively to annular passages 18 and 19, from which rings of ports 20 and 21, respectively, open to the pump cylinders 22 and 23. Working within the cylinders are pistons 24 and 25 at opposite ends of 35 a piston rod 26, connected by a link 27 to the crank 28 on the motor shaft 29. The closed crank case 30 forms a chamber for 40 the reception of a supply of oil 31 which, according to my present invention, serves for the lubrication of all bearing parts.

The lubrication of the lower cylinder 23 and the bearings of the link 27 is effected 45 by splash incident to the rotation of the crank 28, which, during portion of its rotation, enters the oil in the crank case. During operation of the pump, the splash action of the crank results promptly in filling 50 the crank case 30 with oil vapor. This vapor I now lead to the upper cylinder 22 automatically through the longitudinal bore 32 of the piston, the lower end of the bore opening to the crank case, while the 55 upper end opens to the chamber 33 above the upper piston 24. This chamber is closed

by a cap 34 secured to the upper end of the cylinder 22. Consequently, as the piston 24 descends a partial vacuum is created in the chamber 33 sufficient to draw the oil 60 vapor from the crank case through the bore 32 and thus lubricate the wall of the cylinder 22. In order to provide means for regulating the depression created in the chamber 33 on the down stroke of the piston 24, the cap 34 is provided with a regulating valve 35. By adjusting the opening of this valve, a greater or less amount of air is admitted therethrough to the chamber 33 on the down stroke of the piston. 70 This of course determines the depression which exists in chamber 33 and thus controls the amount of oil vapor drawn into the chamber 33 through the bore 32.

The pistons 24 and 25, during the operation of the pump, create depressions in the working chambers of the respective cylinders, piston 24 on the up stroke and piston 25 on the down stroke. These depressions in the working chambers of the cylinders 75 tend to cause the lubricant entering the opposite ends of the respective cylinders to work past the pistons and into the working chambers. The entire cylinder walls are thus lubricated.

The adjacent ends of the cylinders are closed by the valves 36 and 37 respectively, held to their seats by the interposed spring 38 but opening against the action thereof to permit the air to escape from the respective working chambers as the pistons approach the valves. The piston rod 26 passes through the hubs 39 and 40 of the respective valves, and its bearing in those hubs requires proper lubrication. The lubricant 90 from the wall of cylinder 22 gathers in the coned upper surface of valve 36 and flows by gravity to its bearing hub. Ample lubrication of the valve hubs on the piston rod is 95 provided in this manner.

Excess oil entering the working chambers of the cylinders in the manner stated, is carried past the valves 36 and 37 by the escaping air when the valves open. In order to prevent loss of this lubricant, the space 100 between the adjacent ends of the cylinders 22 and 23 is enclosed by a spacing drum 41, which is ported at 42 to permit the free escape of air discharged past the valves 36, 37. At its inner end the drum 41 extends sufficiently below the upper margin of the cylinder 23 to form a channel 43 in which the 105 110

escaping oil is collected. A return pipe 44 opens from the bottom of the channel 43 to the crank case 30 and leads back to the latter by gravity the collected oil.

5 From the foregoing it is clear that a constant circulation of lubricant is effected through the pump bearings without any other attention than that necessary to maintain the oil in the crank case in proper condition, while excess oil is recuperated and returned automatically to the crank case.

While the construction shown is simple and workable, various modifications will readily occur to those dealing with the problem, which embody the thoughts which underlie the features which I claim as my invention.

I claim—

1. A pair of aligned cylinders, connected 20 pistons working therein, a crank case to which one of said cylinders opens, the opposite end of the other cylinder being closed, an air admission valve in said closed end for regulating the depression in the chamber formed between said end and one of the pistons, and means for leading to said chamber by suction lubricant from the crank case.

2. A pair of aligned cylinders having discharge ports at their adjacent ends, a pair 30 of connected pistons working in said cylinders, a crank case oil supply, and means for leading lubricant from said supply to the far ends of said cylinders and discharging excess lubricant from their adjacent ends 35 incident to the reciprocation of the pistons.

3. A pair of aligned cylinders having discharge ports at their adjacent ends, a pair 40 of connected pistons working in said cylinders, a crank case oil supply, and means for leading lubricant from said supply to the far ends of said cylinders and discharging excess lubricant from their adjacent ends 45 incident to the reciprocation of the pistons, together with a spacing drum between the cylinders adapted to receive the discharged lubricant, and means for returning said lubricant to the crank case.

4. A pair of aligned cylinders having discharge ports at their adjacent ends, valves 50 for said ports, pistons working in said cylinders, a piston rod passing through said valves and connecting said pistons, a crank case oil supply, and means for lubricating both cylinders and the bearing of said piston rod in said valves from said oil supply.

5. A cylinder, a valve at one end thereof, a piston working in the cylinder, a piston rod working through the valve, means for lubricating the cylinder, said valve being shaped to gather excess lubricant from the cylinder and lead it to the piston rod bearing in said valve.

6. A cylinder closed at one end, a piston working in said cylinder, a crank case, a piston rod having a passage opening therethrough from the crank case to the chamber between the closed end of the cylinder and the piston, a regulating valve in said closed end for varying the depression in said chamber incident to the operation of the piston, and lubricant in the crank case passing through the piston rod to said chamber under the influence of such depression.

In testimony whereof I have signed my name to this specification.

OTTO HAENTJENS.
